FIREPLACE

Silvano E. Salvador, 24634 Five Mile Road,
Detroit, Mich. 48239

Filed Nov. 7, 1969, Ser. No. 19,983

Term of patent 14 years

Int. Cl. D23—03

U.S. Cl. D23—97

FIG. 1 is a perspective view of a fireplace adapted for disposition adjacent the corner of a room and showing my new design;

FIGS. 2, 3 and 4 are plan, side elevational and bottom views thereof, respectively;

FIG. 5 is a perspective view of a second embodiment of the fireplace in FIG. 1 and which is adapted for disposition adjacent one wall of a room; and

FIGS. 6, 7 and 8 are plan, side elevational and bottom views thereof, respectively.

I claim:

The ornamental design for a fireplace, substantially as shown and described.
